UNITED STATES PATENT OFFICE

154,754

DESIGN FOR A NEEDLE THREADER OR THE LIKE

Albert E. Edwards, New York, N. Y.

Application October 9, 1947, Serial No. 141,819

Term of patent 7 years

(Cl. D3—19)

To all whom it may concern:

Be it known that I, Albert E. Edwards, a citizen of the United States of America and a resident of the city, county, and State of New York, have invented the new, original, and ornamental Design for a Needle Threader or the like of which the following is a specification, reference being had to the accompanying drawing, forming part thereof, in which:

Fig. 1 is a perspective view of a needle threader showing my new design, a dotted needle being included for purposes of illustration;

Figure 2 is a sectional view on line 2—2 of Figure 1;

Figure 3 is a front end elevation of my needle threader;

Figure 4 is a top plan thereof; and

Figure 5 is a rear end elevation thereof.

I claim:

The ornamental design for a needle threader or the like, as shown and described.

ALBERT E. EDWARDS.
